The ornamental design for a scissors lockout clamp, as shown and described.

DESCRIPTION

FIG. 1 is a front, top and left end perspective view of a scissors lockout clamp showing my new design in use, the portion of the figure shown in broken lines representing a valve, lock cable and padlock and forming no part of the claimed design;

FIG. 2 is a front, top and right end perspective view thereof showing the design in an open position;

FIG. 3 is a front elevational view thereof, the rear elevational view being a mirror image;

FIG. 4 is a left end elevational view thereof;

FIG. 5 is a right end elevational view thereof;

FIG. 6 is a top plan view thereof; and,

FIG. 7 is a bottom plan view thereof.

FIGS. 1 and 3 through 7 show the design in a closed position.

FIG. 3

FIG. 4

FIG. 5

FIG. 6

FIG. 7
